UNITED STATES PATENT OFFICE

RUDOLF DAHMS, OF BERLIN, GERMANY, ASSIGNOR TO SIEMENS & HALSKE AKTIEN-
GESELLSCHAFT, OF WERNERWERK SIEMENSSTADT, NEAR BERLIN, GERMANY

TELEPHONE SYSTEM

Application filed May 14, 1930, Serial No. 452,417, and in Germany May 6, 1929.

The invention relates to a circuit arrangement for automatic telephone systems, in which lines of different length are connected together over selecting devices. It is known that the long lines have a greater damping 5 than the short ones, so it is necessary to insert amplifiers in the connections set up over long lines, while the insertion of amplifiers is not required when shorter lines are connected together.

Now the object of the invention is to effect in an entirely automatic and suitable manner the switching in of the amplifiers in those cases where this insertion of amplifiers is necessary; and according to the invention this is achieved in that after all the switches, which serve to set up a connection between an incoming line and a line outgoing in the required direction, have been positioned, switching means come into action that determine, according to the incoming and outgoing lines, whether an amplifier is to be inserted in the interconnected lines or whether the lines remain interconnected without the insertion of an amplifier.

Three methods of carrying out the invention are hereafter described and shown in the drawing.

Fig. 1 shows a method of carrying out the invention whereby a telephone station over an incoming line from a distant exchange sets up a connection automatically to another telephone station, which is also connected to a long line, this being done by means of an impulse sender. After the connection has been set up, the amplifiers are switched in, this being done over a special by-path, over which subsequently the speaking connection extends, while the connecting route over the various selecting stages for setting up the connection is entirely disconnected after the amplifier has been switched in. The circumventing of the switches over which the connection is set up has the advantage that a reduced number of group selectors can be provided, because they are used only during the comparatively short time occupied in setting up the connection and they are released as soon as the amplifier has been switched in.

Fig. 2 shows another method of carrying out the invention wherein the amplifiers are switched into the connecting route, for example between the selecting stages, the connecting route being opened after the amplifiers have been switched in.

Fig. 3 shows an arrangement similar to Fig. 2, but here the amplifiers are directly switched onto the connection, in the example shown they are switched onto the incoming 60 junction line. Obviously the connecting up could also be effected at the outgoing line. Here also the connecting route is opened after the connection has been set up.

The method of setting up a connection will 65 first be described with reference to the arrangement shown in Fig. 1. It will be assumed that a telephone station making a call over the junction line VL 1 incoming from a distant exchange wishes to set up a connection with a telephone station that can be reached over the junction line VL 2, which may extend over other exchanges. The junction lines VL 1 and VL 2 are long junction lines requiring an amplifier to be switched 70 in when they are interconnected. In the present case it is assumed that the exchanges located in the connecting route are automatic exchanges whereby the subscribers can set up 75 a connection without the assistance of a trunk operator.

When the calling station initiates a call over the incoming line VL 1, the relay C 1 associated with the incoming line VL 1 in known manner is energized over: earth, battery, 85 winding of relay C 1, contact 20 u 1, lead a and earth at the preceding exchange. Relay C 1 operates its contacts. The incoming current impulses energize the relay J located in the incoming junction line and in accordance with the impulses its contact 2 j applies earth to the a lead of the junction line VL 1, thereby the relay A 1, which likewise is connected to the a lead, is energized at each impulse in the circuit over: earth, battery, winding of relay A 1, contact 9 w, lead a, contacts 21 u 1, 2 j, earth. Each time relay A 1 is operated its contact 3 a 1 is closed, whereby the lifting magnet H of the first group selector I.GW is energized over earth and 90 95 100

contact 4 *w*, the relay P 1 being energized in parallel therewith over its winding III. Magnet H raises the wipers of the switch to the desired level and relay P 1 short circuits its winding I over its contact 10 *p* 1. This short circuit of its winding I causes the relay P 1 to remain energized during the impulse transmission. On falling back at the end of the impulse train the relay A 1 opens the circuit of the lifting magnet H and of relay P 1, hence over the off-normal contact 22 *k*, which was closed at the first lifting step, the now closed contacts 6 *p* 1, 5 *a* 1, and 23 *c* 1, the rotary magnet D of the switch is connected up and sets its wipers in motion. At the first rotary step the contact 8 *d* is closed and 9 *w* is opened, and the switch is moved on step by step in known manner by the interaction of the rotary magnet D and the relay A 1, which operate as a relay interrupter. During this time the opened contact 9 *w* disconnects relay A 1 from the lead *a*.

When the wipers of the switch I.GW have reached the contact of a free switch in the next switching stage, for example a free II.GW, the relay P 1 is again operated over earth, contact 1 *c* 1, winding I and II of relay P 1, switch wiper and battery at the succeeding switch; by closing its contact 10 *p* 1 it short circuits its winding I, thus the seized switch II.GW is marked engaged to other calls. The junction line VL 1 has now been connected to the switch II.GW over the closed contacts 11, 12 and 13 *p* 1. The selections over the selecting stages II and III GW take place in the same manner as described before, which is known per se. When the last switch in the selecting stage III.GW has been positioned on the line VL 2 going in the desired direction, the seizing relay C 2 is energized over its winding I associated with the outgoing end of the junction line VL 2; by closing its contact 54 *c* 2 it seizes at the terminal exchange of the outgoing line VL 2 a switch for selecting the subscriber or an outgoing junction line.

After the connection has been established over the switches I, II and III.GW, the relay K at the incoming end of the junction line VL 1 is operated at the same time and closes its contact 14 *k*, thereby operating at the call distributor AO the relay R 1 over: earth, contacts 14 *k*, 15 *p* 3, winding of relay R 1, battery, earth. At its contact 16 *r* 1 the relay R 1 closes the circuit for the rotary magnet D 1 of the assignor over: earth, contacts 17 *p* 3, 16 *r* 1, winding of D 1, battery, earth. The step-by-step movement of the switch is effected in known manner by the rotary magnet D 1 operating alternately with the relay R 1, so that the call assignor AO takes a step each time the circuit of D 1 is closed; after each step the relay R 1 is short circuited over the closed contact 18 *d* 1 and at contact 16 *r* 1 it opens the circuit of the rotary magnet.

Contact 18 *d* 1 is opened again, relay R 1 is again operated and contact 16 *r* 1 again closes the circuit of D 1.

When the wiper of the call assignor AO has reached the lead going to the fourth wiper of the first group selector, the relays P 3, B 1 and B 2 are simultaneously operated in a circuit over: earth, winding of relay P 3, switch wiper, relay B 1, contact 19 *u* 1, key Ta 1, contact 13 *p* 1, the switches at each selecting stage I, II and III GW, key Ta 2, winding of relay B 2, battery, earth. These relays operate their contacts. Relay P 3 at its contact 17 *p* 3 opens the circuit of the rotary magnet D 1, which is arrested and at contact 15 *p* 3 it opens the circuit of relay R 1, which opens its contact 16 *r* 1.

Relay P 3 at the same time over contact 24 *p* 3 closes the circuit of relay R 2 at the amplifier distributor VV. The amplifier distributor VV is always standing on a free amplifier set, which is designated by the contact 55 *z* being in its normal position.

In its normal position contact 25 *t* is closed and 56 *t* is open. Relay T is energized over its winding II and contact 55 *z*, hence in the operating position contact 25 *t* is open and 56 *t* is closed.

Therefore when contact 24 *p* 3 is closed, the relay R 2 is operated and preparatorily closes its contacts 27 and 28 *r* 2 as well as closing its contact 29 *r* 2. Over the latter are started up the rotary magnets D 3 and D 4 of the switches AW 1 and AW 2, which connect up the free amplifier set, and the wipers of the switches are rotated until they have found the calling and called lines, which are indicated by the closed contacts 34 *b* 1 and 35 *b* 2. The step-by-step movement of D 3 and D 4 is due to the alternate interaction of the relay R 2 with the rotary magnets D 3 and D 4, which at their contacts 29 *d* 3 and 30 *d* 4 alternately short circuit relay R 2, while relay R 2 at its contact 29 *r* 2 alternately closes and opens the circuit of the rotary magnets.

When the wipers of the switches AW 1 and AW 2 reach the contacts of the calling and called lines, the relays P 4, U 1 belonging to the calling line VL 1 and the relays P 5, U 2, C 2 winding II belonging to the outgoing line VL 2 are operated in the following circuit: earth, contact 27 *r* 2, relay P 4 windings I and II, switch wiper, contacts 31 *c* 4, 34 *b* 1, winding of relay U 1, battery, earth; as well as: earth, contacts 28 *r* 2, 57 *z*, windings I and II of relay P 5, switch wiper, contact 35 *b* 2, winding of relay U 2, winding II of relay C 2, battery, earth. The relays P 4 and P 5 at their contacts 58 *p* 4 and 59 *p* 5 open the circuits of the rotary magnets D 3 and D 4 of the amplifier selectors AW 1 and AW 2, so that the latter are arrested. At the same time are closed the contacts 60 *p* 4, 53 *p* 4 and 36 *p* 5 in the circuits of the relays U 1, P 4, 134

U 2 and P 5 as well as the contacts 32 p 4 and 78 p 5 and contact 73 p 5 is opened. Over the contacts 32 p 4 and 78 p 5 the relay Z is operated and actuates its contacts. Over the contacts 61, 37, 38, 39, 40, 41, 42, 43 and 44 z the amplifier is switched into a separate by-path connected to the calling and the outgoing junction lines VL 1 and VL 2. The windings II and I of relays P 4 and P 5, respectively, are short circuited over the closed contacts 62 z and 57 z, thus marking the switches AW 1 and AW 2 engaged.

When relay Z operated it also opened its contact 55 z, thereby allowing relay T to release and open its contact 56 t to bring about the release of relay R 2 and close its contact 25 t. The closing of contact 25 t energizes the rotary magnet D 2 of the amplifier distributor VV and the interaction of the rotary magnet D 2 and relay T then moves the switch VV to the next free amplifier in known manner.

The relays U 1 and U 2 lying in the same circuit as the relays P 4 and P 5 are energized at the same time as the latter and have connected one end of the leads of the by-path over the contacts 65, 66 and 49 u 1 to the calling junction line VL 1 and over the contacts 67, 68 u 2 and 50 u 2 to the outgoing junction line VL 2. Contact 20 u 1 connects the relay C 4 in place of relay C 1 to the lead c of the calling line.

The connecting up of the by-path to the junction lines VL 1 and VL 2 and the simultaneous opening of the contacts 45, 46 and 21 u 1 and 47 and 48 u 2 caused the connecting route set up over the selecting stages I, II, and IIIIGW to be disconnected and released, and the speaking route now extends over inserted amplifier and the leads of the by-path connecting the amplifier to the lines VL 1 and VL 2. Contact 54 c 2 is kept closed in the c lead of the junction line VL 2, because after the opening of contact 70 u 2 has de-energized winding I of relay C 2 the latter is held over its winding II located in the circuit of the relays P 5 and U 2. On being operated, the relay U 1 at contact 19 u 1 opens the circuit of the relays K, P 3, B 1 and B 2, and they fall back. Relays B 1 and B 2 open their contacts 34 b 1 and 35 b 2 in the circuit of relays U 1, P 4, U 2 and P 5, which are held over the contacts 71 u 1 and 31 c 4 and 32 u 2 that have been closed in the meantime. Relay P 3 closes its contacts 15 p 3 and 17 p 3 and the call assignor AO is now free for other calls.

As soon as the calling station now transmits the other impulses for reaching the wanted subscriber, the relay J, which lies in the incoming junction line VL 1, receives impulses, at each of which its contact 2 j applies earth to the lead a. The impulses now go over the third lead of the by-path and energize the relay A 2 in the outgoing junction

line over: earth, contacts 2 j, 49 u 1, wiper of switch AW 1, contact 61 z, wiper of switch AW 2, contact 50 u 2, lead a, choking coil 1 DR I, relay A 2, battery, earth. Relay A 2 repeats the impulses by closing its contacts 51 a 2 and 52 a 2, thereby applying the alternating current source to the junction line VL 2. This further selection can be effected satisfactorily in every case, that is to say also when for example the relays U 1 and U 2 have not yet been energized or their contacts are in the act of being switched over. In that condition the impulse transmission takes place either over the contacts of the relays U 1 and U 2, which are still connected to the a lead or over their contacts already connected to the third lead of the by-path.

At the end of the conversation when the calling subscriber hangs up his receiver, the relay C 4 at the incoming end of the junction line VL 1 is de-energized and at contact 31 c 4 it opens the circuit of the relays U 1 and P 4, whereupon these relays fall back. Over the contact 53 p 4 the circuit of the relays P 5 and U 2 and winding II of relay C 2 is also opened, thereby releasing the connection. Relay Z is energized until the relays P 4 and P 5 have fallen back and its winding is short circuited at contact 73 p 5. The release of the switches in the preceding distant exchange was also initiated when the relay C 4 belonging to the incoming junction line VL 1 fell back.

For certain reasons it will not always be necessary to use amplifiers for connections over long lines. To provide for this two keys Ta 1 and Ta 2 are inserted in the circuit of the fourth switch wiper. Pressing these keys opens the circuit over the fourth switch wipers and relay K, hence this relay and likewise the relays P 3, B 1 and B 2 cannot be operated and the amplifiers therefore are not connected up.

In the foregoing it has been described that the designation for the connecting up of the amplifiers takes place over the relay K located in the circuit of the fourth switch wiper. This designation can also be so arranged that for example the fourth switch wiper is omitted. The connecting up of the relays K, B 1 and B 2 then takes place over the lead b of the setting up route as is shown dotted in the Fig. 1 of the drawing. The circuit of relay K then extends from earth over the winding of the relay K, contact 19 u 1, key Ta 1, contact 13 p 1, choking coil II Dr, lead b, switch, b lead, choking coil II Dr 1, key Ta 2, winding of relay B 2, battery, earth.

When the station calling over the incoming line VL 1 sets up a connection to a station accessible over the short line VL 4, the connection is set up over the selecting stages I, II and IIIIGW in the same manner as previously described. The line VL 4 being a short line, it is not necessary to insert an amplifier

when such a line is connected to the line VL 1, and, therefore, the line VL 4 does not have the means for connecting up amplifiers, for example the relay B 2. Hence no amplifier can be inserted, because the absence of this means at this line also prevents the means at the calling line (relay K, B 1) being operated. The lines remain connected together over the route, that is to say over the switches, used for setting up the connection; thus this connecting route also forms the speaking route.

The same applies to the interconnecting of two short lines, for example VL 3 and VL 4. The connection is set up in the same manner as that previously described. As none of these lines have the means (relays K, B 1 and B 2) for connecting up the amplifiers, the latter cannot be inserted. The speaking route extends over the setting route, that is to say over the switches.

In the example according to Fig. 2 it will be assumed again that a station calling over the junction line VL 1 sets up a connection to a station that can be reached over the line VL 2. Contrary to the example according to Fig. 1, the insertion of the amplifier, instead of being inserted over a special by-path, is directly inserted in the connecting route, namely between two selecting stages, which are assumed to be the first and second group selectors I. and II.GW.

When the connection has been set up over the different selecting stages in a manner similar to that described in the first example, the relay A belonging for example to the first group selector and the relay B belonging to the second group selector are operated. At their contacts 101 a and 102 b they close a circuit for the relay C. The latter actuates its contacts 103 c to 108 c, thus connecting up the amplifier V. The contacts 103, 104 and 105 c at the same time disconnect the connecting route. The speaking route extends over the amplifier and the selecting stages located in front and beyond it, that is to say over the setting route and the inserted amplifier.

In this example when the station calling over the incoming line VL 1 sets up a connection to a station that can be reached over the short line VL 4, no amplifier is inserted, because the means, i. e. the relay B is missing from it. The circuit of relay C remains open, the connecting up of an amplifier is prevented.

When a station calling over the short line VL 3 sets up a connection to a station that can be reached over the short line VL 4, again no amplifier is connected up, because none of these lines have the means for connecting up the amplifiers.

In general the same remarks apply to the example shown in Fig. 3 as to the second example. The difference between them is that

the amplifiers in the example 3 are directly connected to the lines as shown for example to the incoming line VL 1. Obviously the connecting up could also be effected for example at the outgoing line VL 2.

The long lines, for example VL 1 and VL 2 have a relay A associated with each incoming line and a relay B with each outgoing line, these form the means for connecting up the amplifier. The relays lie in a circuit over a special switch wiper. The circuit is closed when the setting up over the different selecting stages has been completed. When relay A is operated the switching over of its contacts 121 a to 126 a connects the amplifier to the incoming line VL 1 and at the same time the operated contacts 121, 122 and 123 a open the connecting route. The speaking route extends over the amplifier and the different selecting stages.

What is claimed is:

1. In a telephone system, an incoming line, an outgoing line, automatic switches controlled over said incoming line for interconnecting said lines, an amplifying device, and means responsive to said interconnection for directly connecting said lines through said amplifying device and for releasing said automatic switches.

2. In a telephone system, an incoming line, a plurality of outgoing lines of two classes, a train of automatic switches controlled over said incoming line to select any one of said outgoing lines, an amplifying device, and means effective only if the selected line is of a particular class for substituting said amplifying device for said train of automatic switches.

3. In a telephone system, a plurality of incoming lines divided into two classes, an outgoing line, a train of automatic switches controlled over a calling incoming line to connect with said outgoing line, an amplifying device, and means effective only if said calling line is of a particular class for substituting said amplifying device for said train of automatic switches.

4. In a telephone system, an incoming line, a plurality of outgoing lines divided into two classes, automatic switches controlled over said incoming line for selecting any one of said outgoing lines, an amplifying device, and means effective if the selected line is of a particular class for inserting said amplifying device in the connection between the incoming and the selected outgoing line.

5. In a telephone system, a plurality of incoming and outgoing lines, means controlled over a calling incoming line for connecting the line to one of said outgoing lines, discriminating means associated with certain of said lines having predetermined characteristics, a repeater, and means controlled by said discriminating means and effective only if both of said interconnected lines are of

said characteristics for automatically including said repeater in said connection.

6. In a telephone system, a plurality of incoming and outgoing lines divided into two classes, a train of automatic switches operated over a calling incoming line to connect with one of said outgoing lines, a plurality of common link circuits each comprising a repeater and two finders, means effective only if both of the connected lines are of a particular class for associating an idle link circuit with said connection, and means for operating said two finders to connect with the incoming and the outgoing line, respectively, thereby completing said connection through said repeater.

7. In a telephone system, a plurality of incoming and outgoing lines divided into two classes, a train of automatic switches operated over a calling incoming line to connect with one of said outgoing lines, a plurality of common link circuits each comprising a repeater and two finders, means effective only if both of the connected lines are of a particular class for associating an idle link circuit with said connection, means for operating said two finders to connect with the incoming and the outgoing line, respectively, thereby completing said connection through said repeater, and means for thereafter releasing said train of automatic switches.

8. In a telephone system, a plurality of incoming and outgoing lines divided into two classes, automatic switches controlled over a calling incoming line to connect with one of said outgoing lines, a plurality of common link circuits each including a repeater, and means operative only if both of the connected lines are of a particular class for replacing said automatic switches with an idle one of said link circuits to connect said lines.

9. In a telephone system, a plurality of lines, automatic switches controlled over a calling line for connecting said line to a desired called line, a plurality of common repeaters, and means responsive to said connection for inserting an idle one of said repeaters in the connection between the calling and called lines.

10. In a telephone system, a plurality of lines, automatic switches controlled over a calling line for connecting said line to a desired called line, a plurality of common repeaters, and means responsive to said connection for connecting the calling and called lines through an idle one of said repeaters and for releasing said automatic switches.

In witness whereof, I hereunto subscribe my name this 8th day of April, A. D. 1930.

RUDOLF DAHMS.
